UNITED STATES PATENT OFFICE.

DONALD S. BARROWS, OF ROCHESTER, NEW YORK.

DRAFT-RIGGING.

1,358,499.

Specification of Letters Patent.

Patented Nov. 9, 1920.

Application filed June 30, 1917. Serial No. 177,858.

To all whom it may concern:

Be it known that I, DONALD S. BARROWS, a citizen of the United States, residing at Rochester, in the county of Monroe and State of New York, have invented certain new and useful Improvements in Draft-Rigging; and I do hereby declare the following to be a full, clear, and exact description of the invention, such as will enable others skilled in the art to which it appertains to make and use the same.

The invention relates to the art of draft rigging for railway cars, and more particularly to a combined stop and tie casting designed for coöperation with that type of draft rigging in which the coupler and yoke, or other suitable cushion connecting means, is slidably connected so as to permit the coupler to move rearwardly independently of the said yoke, the combined back stop and tie casting acting to prevent the yoke and cushioning means from moving rearwardly and to distribute to the car sills the loads placed upon the cushioning means in buffing or inward movement of the coupler.

The principal object of my invention is to provide a combined back stop and tie casting for use with draft rigging of the type above set forth, and in combination with a car underframe having a pair of spaced sills and in which the center line of draft is below the center line of the said sills. To this end the main feature of my invention, broadly stated, comprises, a combined stop and tie casting in which the buffing face of the stop casting is reinforced by a transversely extending web which forms, in conjunction with the buffing face and another web of the casting, an "I"-beam section adjacent the central portion of the casting, this section changing to a channel-shaped section adjacent the side flanges or sill adjacent faces of the casting, to allow the insertion and driving of the attaching rivets, above the said transversely extending web, in combination with means to adequately strengthen the casting as a whole against lateral or longitudinal buckling without making the same unduly heavy or large.

There are other features of the invention, as will appear from a more detailed description thereof when taken in connection with the accompanying drawings which are chosen for the purpose of illustrating one embodiment of the invention, and in which:

Figure 1 is a top plan view partially in

section, showing the combined stop and tie casting and the adjacent portions of the draft rigging and car underframe,

Fig. 2 is a central longitudinal vertical section of the structure shown in Fig. 1,

Fig. 3 is a bottom plan view of the combined stop and tie casting,

Figs. 4 and 5 are front and rear elevations, respectively, of the combined stop and tie casting, and

Fig. 6 is a transverse vertical section taken on line 6—6 of Fig. 1, looking in the direction indicated by the arrow, the adjacent sills being shown in dotted lines.

Throughout the specification and drawings like parts are designated by like reference characters.

The draft sills 1 are riveted to the outer faces of the center sills 2 by the rivets 3, 4 is 75 the rear end of the draft yoke, 5 the cushioning means, 5^a the rear supporting strap therefor, and 6 the rear follower.

The combined stop and tie casting 7 preferably comprises a pair of spaced longitudinally extending webs or flanges 8, the outer faces of which are adapted to contact with the inner or adjacent faces of the center sills 2, the flanges 8 each being connected to the web of the adjacent sill 2 by means of the rivets 9 and 10. The webs or flanges 8 are each preferably formed with an extension 8^a extending upwardly above the main body of the stop casting, these webs also extend somewhat in rear of the main body of the casting 7, as shown at 8^b. These extensions of the securing flanges 8 provide sufficient space for the employment of the required number of rivets to adequately secure the stop casting to the car sill without weakening the casting by unduly extending the same. The rivets 10 may, and preferably do, extend through the draft sills 1 in addition to the center sills 2. The flanges 8 are, as shown, suitably connected by a web 11, 100 integrally connected to the lower portions of the said flanges; this web 11, adjacent the sides thereof, conforms to the inclination of the lower flanges 12 of the center sills 2, as shown at 13, and may be, and preferably is, 105 connected to these flanges by means of the rivets 14.

Intermediate the portions 13, the web 11 is, for a portion of its length, arched upwardly, as at 15, whereby the central portion of the said web is brought into alignment with the horizontal and longitudinal

axes of the draft rigging, and the casting as a whole is greatly strengthened against longitudinal buckling.

The buffing face 16 of the combined stop 5 and tie casting is formed by a web 17 which is preferably connected at the sides to the side walls or webs 8 by the inclined webs 18. These webs 17 and 18 form, as clearly seen from the drawings, a truncated wedge or 10 pyramid. The webs 17 and 18 are integrally connected to the bottom web 11, and are further braced and strengthened by a horizontally extending web or flange 19 preferably located intermediate the central portion 15 15 of the web 11 and the upper edges of the webs 17 and 18.

The combined back stop and tie casting 7 may be, and preferably is, provided with a centrally located cylindrical opening 20 20 formed in the bottom web 11, which opening is adapted to receive the king bolt on which the car truck turns or pivots. A collar, or cylindrical flange, 21, extends upwardly from the opening 20 and forms an extended 25 bearing for the king bolt. A plurality of bracing webs 22, 23 and 24 are provided, the web 22 extending from the collar 21 to the central portion of the web 17 directly 30 bracing and strengthening both of these members. This web 22, as clearly indicated in Fig. 6, preferably extends both above and below the central portion 15 of the web 11, and forms therewith a cross-shaped member designated as 22^a. The portion of the web 35 22 below the web 15 is preferably braced by a web or flange 25, which extends downwardly from the central portion 15 of the web 11 intermediate the web 17 and the collar 21. The bracing webs 23 extend from 40 opposite sides of the collar 21 to the adjacent side walls, and preferably extend to the upper edge of the extensions 8^a. The web 24, which may be of triangular shape, extends from the collar 21 to the rear portion 45 of the bottom web 11, and is preferably placed diametrically opposite to the web 22.

It will be readily apparent from the disclosure in connection with the foregoing description that the improved form combined 50 back stop and tie casting is adequately braced and reinforced on the center line of draft, and that this bracing does not interfere with the application of sufficient number of rivets to adequately connect the casting to the car sills. In fact, the metal is so distributed throughout the casting that the casting presents in longitudinal vertical section, adjacent its central portion, the highly desirable "I"-beam construction, the flanges 55 60 of said beam being formed by the web 17, and portions of the webs 21 and 23, while the web of the beam is formed by the portion 15 of the web 11; the casting also presents in longitudinal vertical section adjacent the side flanges 8, the desirable channel beam 65

formation heretofore referred to, in which the flanges of the beam are the upwardly extending flanges 18 and 23 of the casting, while the web of the channel is formed by the portion 13 of the web 11. It will thus be 70 evident that I have produced a stop casting for use with cars having a low center line of draft, which casting has the desired formation to secure the maximum strength against longitudinal deformation and which presents 75 at the same time, owing to its channel shape formation, no difficulty in placing or driving of the rivets which serve to connect the casting to the car sills. It will also be evident that the improved form of combined 80 back stop and tie casting, while possessing great strength and rigidity, is, nevertheless, a simple casting and is, therefore, easy to manufacture, and the casting as a whole is adapted to convey to the center sills the load 85 placed upon the casting by buffing or inward movement of the coupler.

Having now described my invention, although it is to be understood that the terms used are to be considered in their descriptive and not their limiting sense, what I claim and desire to secure by Letters Patent is:

1. If a draft rigging, the combination with center sills having inwardly directed 95 lower flanges, of a combined back stop and tie casting fitting between and overlying the lower flanges of the said sills, said casting comprising a plurality of side walls and a transversely extending connecting web, the 100 central portion of said web being raised above the side thereof, and rivets for connecting said casting to the said sills, said rivets passing through the sides of the said webs and through the adjacent flanges of the 105 said sills.

2. In a draft rigging, the combination with flanged center sills having the lower flanges thereof inwardly extending, of a combined back stop and tie casting adapted 110 to fit between and be secured to the adjacent portions of the said sills, said casting being provided with a transversely extending web having a raised central portion and, portions which are adapted to seat on the said flanges 115 of the said sills, and means for rigidly connecting the said portions to the said flanges.

3. In a draft rigging, the combination with a pair of spaced sills, of a combined stop and tie casting fitting between and secured to said sills, said casting being provided with a buffing plate and vertical side walls, and means for integrally connecting the same, said means including a transversely extending web or flange, the central 120 125 portion of said flange being arched upwardly.

4. In a draft rigging, the combination with a draft yoke and cushioning mechanism, of a combined back stop and tie cast- 130

- ing having upright side walls, said casting being provided at its forward end with a buffing face formed by a vertically extending web, means for reinforcing said web, 5 said means including vertical and horizontal intersecting webs, said last mentioned web being integrally connected to said first mentioned web and to the lower edges of the said side walls and being adapted to intersect the vertically extending web substantially in alignment with the longitudinal axis of said cushioning mechanism.
- 10 5. A combined stop and tie casting comprising a buffing plate, vertical side walls, a plurality of vertical webs adapted to connect the buffing plate to the said walls, a plurality of horizontally extending webs located intermediate the upper and lower edges of said plate, and adapted to integrally connect the same to the side walls, and 15 a vertical longitudinally extending web also connected to said plate and adapted to intersect said horizontal webs.
- 20 6. A combined stop and tie casting comprising a pair of upright longitudinally extending webs, a pair of upright transversely extending webs connecting said longitudinally extending webs, and a transversely extending web connected to said longitudinal 25 webs adjacent the lower edges thereof and connected to the central portions of said upright transversely extending webs at points removed from the upper and lower edges thereof.
7. A combined stop and tie casting comprising a plurality of upright longitudinally extending webs, a plurality of upright transversely extending webs, connecting said first named webs, and a transversely extending web connected to all of said webs, said last 30 named web having its central portion arranged above the horizontal planes of its side portions.
8. A combined stop and tie casting comprising a pair of spaced upright side flanges, 45 a pair of upright transversely extending webs connected to said flanges, one of said transversely extending webs forming a buffing face, and a transversely extending web connected to said flanges adjacent the 50 lower edges thereof and to said transversely extending upright webs, the central portion of said transversely extending web being connected to said upright transversely extending webs at points substantially midway of their height.
- 55 In testimony whereof I affix my signature.
DONALD S. BARROWS.
